UNITED STATES PATENT OFFICE.

HENRY L. DOHERTY, OF NEW YORK, N. Y.

PROCESS OF HEAT REGENERATION.

1,173,999.

Specification of Letters Patent. Patented Feb. 29, 1916.

Application filed December 31, 1909, Serial No. 535,841. Renewed March 21, 1913. Serial No. 756,020.

To all whom it may concern:

Be it known that I, HENRY L. DOHERTY, a citizen of the United States, and a resident of New York city, in the county of New York and State of New York, have invented 5 certain new and useful Improvements in Processes of Heat Regeneration, of which the following is a specification.

This invention relates to a process of heat 10 regeneration, and, in particular, to a process for securing heat regeneration in kilns for the burning of lime, brick kilns, billet re-heating furnaces, etc., with special reference to its use in connection with the inventions 15 which are the subject of my Letters Patent No. 938,987, dated Nov. 2nd, 1909, and of my co-pending application Ser. No. 525,890, filed Oct. 29th, 1909.

In the accompanying drawings, I have 20 illustrated the application of this present invention to the apparatus of the above mentioned Letters Patent and application for Letters Patent, and have, hereinafter, described such application of my invention 25 in detail. It is to be understood, however, that I do not limit this present invention to use in connection with the above mentioned inventions.

This invention is designed specially to be 30 used in connection with the burning or heating of materials such as ordinary building brick, which possess a high thermal capacity but require in their burning a long flame of moderate temperature, and in particular in 35 connection with the heating of materials according to the manner described in said patent. In the burning of such materials in this manner or in the ordinary manner we are confronted with two interfering requirements. In bringing the material up to 40 the temperature of burning, even though the latter is moderate—say 1600 to 1700° F.—a large quantity of sensible heat is stored in the material. In order to recuperate this 45 heat, it must be taken up by the air, or air and gas, supplied to combustion zone of the kiln. Now, in such a case as we are considering, the quantity of air required for the combustion taking place, is much less than 50 that which would be necessary to recuperate the sensible heat, which the bricks carry out of the combustion zone. If now we increase the quantity of air admitted to the base of 55 the kiln to that required to take up the heat of the bricks and return it to the combustion region, we must, in the ordinary way

of burning, have an excess of air in the combustion zone. This causes the combustion to take place with a sharp, intense flame, with a moderate excess of air. The result 60 is that the burning is very irregular. The bricks in immediate contact with the flame are over-burned, while those not in contact with the flame are under-burned. The practical effect of this is, of course, a very un- 65 uniform product, with a large proportion of rejects.

By my invention I can conduct the burning operation with just the proportion of air necessary to give the quality of flame 70 that I desire and yet am enabled to pass through the cooling chamber and preheating chamber of the kiln the requisite quantity of air to insure the substantial recuperation of the sensible heat of the bricks. I accomplish 75 this result in a kiln of the described type by introducing into my kiln or burning chamber a by-pass consisting of a plurality of off-take ports below the gas-admission ports, corresponding inlet ports in the kiln 80 walls well above the combustion zone, where the excess of air will have no effect on my flame, and a suitable flue or flues connecting the "off-take" and inlet ports. These ports and flues are made of such size that the re- 85 tardation exerted upon the air current passing through them by friction will be practically negligible. When the apparatus is properly designed the resistance to the passage of the air current is less in the by-pass 90 flues than in the kiln shaft itself. The result, of course, is that a portion of the air current seeks this path of least resistance and passes around the combustion zone of the kiln through the by-pass flues. The pro- 95 portion of the air, so passing, is regulated by the adjustment of the proper dampers located in the by-pass flues. When the conditions are such that the draft through the by-pass flues is not sufficient to overcome the 100 draft of the stack itself I have recourse to arrangement of a positive circulating device (a fan or some equivalent device) interposed in the by-pass conduit to overcome the stack draft and draw off the desired pro- 105 portion of air below the combustion zone—the same being returned to the stack above the combustion zone.

In the drawings, Figure 1 shows a vertical section through a kiln for burning 110 bricks of the general type shown in my application for Letters Patent, Ser. No.

525,390, modified for applying my present invention on the line C D of Fig. 2. Fig. 2 is a partial horizontal section through the battery on the line A B of Fig. 1. Fig. 3 is a partial vertical section through one of the individual kilns on the line E F of Fig. 2. Fig. 4 will answer for a partial horizontal section on either of the lines G H or G' H' of Fig. 1, *i.e.*, through either 10 the air inlet-ports above the combustion zone or the air off-take ports below the combustion zone. Fig. 5 shows a vertical section, through a kiln of circular cross-section, on the line G'' H'' of Fig. 6, with a 15 positive draft-producing device interposed in the air conduit connecting the air off-take and inlet ports. Fig. 6 is a horizontal section through the line I J of Fig. 5; Fig. 7 is a horizontal section through the line K L 20 of Fig. 5; and Fig. 8 is a horizontal section through the line M N of Fig. 5. Fig. 6 will also answer for a horizontal section on the line O P of Fig. 5 as they would appear the same, with the exception that the producer-gas conduit would not be in section.

1', 1'', etc., indicate the individual kilns of a battery. The method of operation is the same in all kilns, so I will restrict the following description to kilns 1' and 1'', 30 provided with natural and positive draft, respectively, in the air diversion-flues.

2 indicates the side walls of kiln 1'; 3, the end walls.

4 is the shaft of the kiln; 5, 5, etc., are 35 ports for the admission of air, having dampers 6.

7 refers to the "cooler" or lower part of shaft 4.

8, 8, etc., are air off-take ports; 9, 9, etc., 40 are gas inlet ports; 10, 10, etc., are vertical flues built in the kiln walls, whose upper ends communicate with the shaft of the kiln through the passages 11 and whose lower ends communicate with the ports 8.

45 12 are dampers regulating the draft through the flues 10 which are accessible through the hand-holes 13, having covers 14.

15 indicates the combustion zone of the kiln; 16 are auxiliary air ports communicating with flues 10, access to which is had through hand-holes 17 through which the laterally-movable dampers 18 may be adjusted.

19, 19, etc., are ports for drawing off a 55 portion of the combustion gases under the action of an injector or fan. These combustion gases are then supplied to the fuel bed of the gas producer 20. In contact with the hot fuel in 20, a portion of the CO₂ parts

60 with one-half of its oxygen to the carbon to generate carbon monoxide—an equal volume of the same gas being at the same time formed by the reduced CO₂. This reaction, which is a highly endothermic one, absorbs 65 that portion of the sensible heat which the

combustion gases have carried out of the kiln which is above the temperature plane of the fuel bed. At the same time, for a given amount of combustible gas required, this circulation of a portion of the hot combustion gases from the combustion zone, permits of a reduction to the minimum of the atmospheric air required in the gas producer, and thus correspondingly reduces the heat drain on the system and permits of the 70 heating of the bulk of the air required by the system by heat recovered from the burned material. Only the relatively small quantity of air required to supplement the heat carried by the combustion gases in 75 order to maintain the fuel bed of the producer at a reactive temperature is supplied to the same. Since, as stated in the application referred to, I pass the draft current of combustion gases through the producer under conditions such that only a portion of their CO₂ is dissociated, the combustible gas produced is diluted with a comparatively considerable proportion of noncombustible 80 gases. This modified producer gas passes 90 to the kiln through the conduits shown and is introduced into the lower portion of the combustion zone 15 through the ports 9. In 15 the gas is burned by that portion of the air which is permitted to ascend into 15 95 from the cooler 7, with the production of a dilated flame of moderate temperature, which enables me to secure an active circulation of the flame around and in contact with all portions of the charge in 15. At the 100 same time the increased volume of the combustion gases passing through 15, due to the unchanged combustion gases circulated back to the same from the ports 19, greatly 105 increases the velocity of flow through 15 and hence, in direct proportion, the heating effect of the gases. By thus combining into an improved process the combustion gas circulation of application 525,390 and the air circulation herein disclosed I have 110 devised an improved process of heat recuperation which permits of the securing of a greater heat economy, in the operation of apparatus of the type referred to, than is possible by the methods of operation at present known to the art.

As the combustion gas circulation, in the embodiment of my invention as applied to the operation of a kiln as an improvement upon the process of my Letters Patent No. 120 938,987, above referred to, is substantially the same as described above, no further detailed description of the same is necessary.

In the type of kiln 1''', shown in Figs. 5 to 8, provided with forced circulation of air, 125 21 refers to that portion of the kiln shaft which I designate as the pre-heating chamber.

22 indicates a draft-producing means, discharging into a conduit 23.

When the kiln is in normal operating condition the shaft 4 is filled with bricks, limestone, or whatever material is being treated, in various stages of treatment. The air is admitted through the ports 5, provided with dampers 6, passes up through the cooler 7 to the air offtake ports 8. Here it divides into two currents, one, passes directly up through the shaft to burn the gas admitted through the ports 9, the other current passes into the ports 8, up through the vertical connecting flues 10, in the kiln walls, and returns to the shaft through the ports 11. The proportion of air passing through the flues 10 is regulated by adjusting the dampers 12 through the hand-holes, 13, which are ordinarily closed by covers 14. The proportion of air by-passed around the combustion zone, 15, through the by-pass flues seldom exceeds one-half of the total volume of air entering the bottom of the kiln, although I do not restrict myself to the bypassing of any specific proportion since the proportion so by-passed will, of course, depend upon the requirements of each particular case. Usually, I permit to pass up through the stack to the combustion zone just about the theoretical quantity of air for the complete combustion of the gas introduced through 9. Under some conditions, however, I may restrict this portion of the air to less than this quantity, introducing the balance of the air required, to make up this quantity, through auxiliary ports 16, connected with flues 10. Suitable hand-holes 17, provide access to 16, and permit of the adjustment of the laterally-movable dampers 18, to regulate the volume of air passing through 16 to the proper quantity. By this device, I produce a long, slow burning flame of moderate temperature, in which the combustion is not completed, until it has reached a level in the shaft above the auxiliary ports 16. The quantity of air by-passed is fixed by (a) the quantity of air necessary to cool the burned bricks (or other material) and (b) the quantity which is required in the combustion zone proper. It is the difference between the quantities (a) and (b) which I withdraw through 8 and by-pass around the region 15. The ports, 11, are located, preferably, at the height in the kiln at which the combustion gases from the region 15 will, in normal running, have substantially the same temperature as the by-passed air. When, however, as in the particular application of my invention, which we are considering, a portion of the combustion gases are withdrawn from the kiln for use in regulating the thermic conditions in the producer, it is desirable to locate the ports 11 above the combustion gas off-takes 19, thus avoiding the dilution of the combustion gases going to the producer 20.

The by-passed air mingles with the current of combustion gases in what I designate as the preheating region, 21, of my kiln and yields up its heat to the descending unburned material in the region 21. The net result of my process is, therefore, to take up from the finished material that portion of the sensible heat which it carries which the normal quantity of combustion air cannot take up and to transfer this heat to the descending raw material in the preheating region 21. Thus, no matter what the heat capacity of the material passing through the kiln may be, I am able to effect substantially perfect recuperation of the heat which it carries and at the same time conduct my combustion with just the proper quantity of air to secure the conditions which I desire in the combustion region 15. When, as may sometimes happen in the burning of limestone, where the material is in fragments of large size and comparatively large passageways are automatically formed in the charge for the passage of the combustion gases, there may not be a sufficient difference in the draft through the by-pass flues and the stack itself to divert the desired proportion of the air through the by-pass flues, I interpose a positive draft-producing device, 22, in the by-pass conduits, and carry out my process with a modified arrangement shown in Figs. 5 to 8 inclusive. In these figures the parts corresponding in function to the parts shown in Figs. 1 to 4, are designated by the same numerals with the addition of the accent. In this case I have substituted the single conduit 23 for the several flues 10 and carry it up outside the kiln. The method of operation is, however, identical with that of the apparatus, just described.

Having described my invention, what I claim is:—

1. In connection with the operation of a heating or calcining chamber, the process of heat regeneration which consists in passing in contact with the heated material from the combustion zone of said chamber, a current of air, the volume of the said air being sufficient to take up, substantially, all of the sensible heat of the said heated material, whereby the said heated material is cooled and the said air-current heated, dividing the so-heated air current into two streams, at a place in said chamber adjacent to the combustion zone thereof, passing one of said air streams into the said combustion zone, the volume of said air-stream being less than that required to support the combustion taking place in the said combustion zone, conducting the other of said air-streams around the said combustion zone, subdividing the other of said air-streams into a major and a minor portion and uniting said major portion with the products of combustion from the said combustion zone, intro-

ducing the said minor portion into an intermediate region of said combustion zone to complete combustion therein, and passing the commingled stream of heated air and products of combustion in contact with the relatively cold unheated material approaching the combustion zone, whereby the said unheated material is heated and the said stream of heated air and products of combustion cooled.

2. In the operation of a heating or calcining chamber, the process of heat regeneration, which consists in transferring part of the heat of the heated material leaving the combustion zone of said chamber, to the relatively cool material approaching the combustion zone of said chamber, by means of a current of air as a vehicle, and transferring another part of the sensible heat of the heated material to the combustion zone of said chamber by means of the air supplied to said combustion zone as a vehicle, and re-passing a portion of the combustion gases generated in said combustion zone through a comparatively deep bed of incandescent fuel and back to said zone.

3. The process of heat regeneration which comprises passing air in contact with the heated material in a heating chamber, whereby the said air is heated by the sensible heat of said material, the volume of said air being in excess of that required for the combustion in said chamber, dividing said air current into two streams, passing one of said streams into the combustion zone of said chamber, by-passing the other of said streams around the combustion zone of said chamber, contacting the said stream with the relatively cool unheated material approaching the combustion zone, and re-passing through said combustion zone a portion of the combustion gases leaving said zone.

4. The process of heat regeneration which comprises passing air in contact with the hot heated material discharging from the combustion zone of a heating chamber, the volume of said air being in excess of that required for sustaining the combustion in the said combustion zone, whereby the said air is heated and the said calcined material cooled, dividing the so-heated air current into two main streams, passing the first of said streams into the said combustion zone, at that region of the same where the required fuel is introduced thereinto subdividing the second of said main streams into a major and a minor portion, introducing the said minor portion of said second stream into a mid region of said combustion zone, conducting the said major portion of said second air stream around the said combustion zone, uniting it with the products of combustion from the said combustion zone, and passing the commingled streams of

heated air and products of combustion in contact with the relatively cool unheated material approaching the combustion zone, whereby the said uncalcined material is heated and the said stream of commingled air and products of combustion cooled.

5. The process of regenerating heat which comprises providing a moving or traveling body of material passing through a zone of combustion, passing air in heat-absorbing relationship to the hot material passing beyond the zone of combustion, transmitting a portion of the air so heated to said zone to maintain combustion therein, diverting the residue of air so heated around the zone of combustion, passing a portion of said diverted air into contact with the material advancing toward said zone, and re-passing through said zone of combustion a portion of the combustion gases leaving the same.

6. The process of regenerating heat which comprises providing a moving or traveling body of material passing through a zone of combustion, passing air in heat-absorbing relationship to the hot material passing beyond the zone of combustion, transmitting a portion of the air so heated to said zone to maintain combustion of combustible gas therein, diverting the residue of the air so heated around the zone of combustion, passing an admixture of said diverted air with a first portion of the products of combustion into contact with the material advancing toward said zone, diverting a second portion of said products of combustion, contacting said diverted portion of products of combustion with incandescent carbon to generate combustible gas, and introducing said combustible gas into said combustion zone.

7. The process of regenerating heat which comprises providing a moving or traveling body of material passing through a zone of combustion, passing air in heat-absorbing relationship to the hot material passing beyond the zone of combustion, transmitting a portion of the air so heated to said zone to maintain combustion therein, diverting the residue of the air so heated around the zone of combustion, passing an admixture of said diverted air with a first portion of the hot products of combustion leaving said combustion zone into contact with the material, and re-passing a second portion of said products of combustion through said combustion zone to increase the velocity of flow of gases therethrough.

8. The process of regenerating heat which comprises providing a moving or traveling body of material passing through a zone of combustion, passing air in heat-absorbing relationship to the hot material passing beyond the zone of combustion, transmitting a portion of the air so heated to said zone to maintain combustion therein, diverting the residue of the air so heated around the

zone of combustion, passing an admixture of a portion of said diverted air with a first portion of the products of combustion leaving said zone of combustion into contact 5 with the material advancing toward said zone, the admixture being at a point where the temperature of said products is substantially the same as that of said air, introducing another portion of said diverted 10 air into an intermediate region of said combustion zone, diverting a second portion of said products of combustion, contacting said second portion with carbon to change a portion 15 of said products of combustion to combustible gas, and introducing the said products of combustion, after they have been contacted with carbon, into said zone of combustion.

9. The process of heating and heat regeneration which comprises advancing material to be heated to, through and beyond a zone of combustion, cooling the hot material and heating air beyond said zone by a sufficient supply of contacting air, transmitting a limited amount of the air thus heated into said zone to aid and maintain combustion therein, by-passing another portion of the heated air around said zone, diverting a portion of the by-passed air into said zone of combustion 25 at a mid-region thereof to complete combustion therein, admixing with products of combustion and contacting the admixture with the material advancing toward said zone in order to heat said material.

35 10. The process of heat regeneration which comprises advancing material to be heated to, through and beyond a zone of combustion, and in its progress toward said zone heating the material by contacting with an admixture of heated air and products of 40 combustion, in its progress through said zone heating the material by combustion in the presence of a limited amount of heat-

ed air, increasing the velocity of flow of the products of said combustion through said zone by maintaining a circulation of an excess of combustion gases from the discharge end to the fuel admission end of said zone, contacting the hot material in its passage beyond said zone with a relatively large amount of air, introducing a regulated amount of the air thus heated into said combustion zone to support said combustion, and by-passing another portion of said heated air around said combustion zone to form said admixture.

11. The process of heat regeneration which comprises advancing material to be heated to, through and beyond a zone of combustion, and in its progress toward said zone heating the material by contacting with an admixture of heated air and products of combustion, in its progress through said zone heating the material by a long comparatively cool flame of gas burning in the presence of a limited amount of heated air, the velocity of flow of the gases from said flame being increased by the addition thereto of combustion gases previously discharged from said zone of combustion, contacting the hot material in its passage beyond said zone with a relatively large amount of air to heat said air, introducing a regulated portion of the air thus heated into said combustion zone to support said combustion, and by-passing another portion of said heated air around said combustion zone to form said admixture.

Signed at New York city in the county of New York and State of New York this 30 30th day of December A. D. 1909.
